R. J. NUNN, OF SAVANNAH, GEORGIA.

Letters Patent No. 64,134, dated April 23, 1867.

IMPROVEMENT IN LAND CONVEYANCE.

The Schedule referred to in these Letters Patent and making part of the same.

TO ALL WHOM IT MAY CONCERN:

Be it known that I, R. J. NUNN, of Savannah, in the county of Chatham, and State of Georgia, have invented a new and useful Improvement in "Land Conveyance;" and I do hereby declare that the following is a full, clear, and exact description thereof, which will enable others skilled in the art to make and use the same, reference being had to the accompanying drawings, forming part of this specification.

Figure 1 is a plan or top view; and

Figure 2, a side elevation.

Similar letters of reference indicate like parts.

A A, in the drawings, represent frames, which at each end are rounded with a curve equal to their height. This frame A is supported upon a series of grooved friction-rollers, B B, each of which series rests upon and is surrounded by a flexible band, C, equal in width to the length of the rollers, the whole surface of which bands, between the points D and E, rests upon the ground between the ground and the friction-rollers, the rollers projecting from the frames sufficiently to prevent the contact of the frames and bands. These bands are ribbed, which ribs catch in the grooves of the rollers. Motion is communicated to the bands C at the point F by means of the driving-wheel G, the friction of the band on the periphery of the wheel being increased by the pressure of two rollers, H H, susceptible of adjustment by set-screws I I. J is the steam boiler; K, the steam cylinder, having piston; L, the connecting-rod, and M a cock in the steam pipe N to regulate the speed by varying the supply of steam. The friction-rollers and the driving-wheel are grooved to accommodate the projection or rib of the band, the purpose of this projection being to serve the purpose of a guide and to prevent the band from slipping off of the rollers. The bands may be made of wrought steel, flat chain, and the projections or ribs of fine steel wire interlocked with or wrought in the chain-work of the band. In the drawing only one application of the principle of the pulley to land conveyance is illustrated, but it is obvious that the methods of application admit of many variations; for example, the rope or rib used for a guide to the band may be replaced with cogs or teeth worked in the band, and would answer the double purpose of guides to prevent the band from slipping out of place, and to increase the friction on the driving-wheel, which could be correspondingly cogged or toothed in its groove, or the teeth could be made on the rollers and driving-wheel and the band be made with slots or cavities for the teeth to mesh in, or there may be other guides at the sides to keep the band in place. The number of bands may be more or less, and also the number, form, and size of the friction-rollers may be varied, as well also as the position, size, and number of the driving-wheels, and the manner of communicating power and producing motion in the band; still the principle of operation will be the same. In order to guide the machine it is only necessary to vary the velocity of one band with regard to the other, and if a double-cylinder steam engine is the power employed this may be done by operating the throttle-valve of one or the other side, according to the direction in which the machine is to move. If, however, a single cylinder is the motor some suitable mechanism, such as cone-pulleys, gears, etc., may be employed.

The advantages claimed for a machine on this principle are:

First. By the increase of bearing surface the pressure per square inch upon the ground can be reduced far below that exerted by a man; as, for example, suppose the square inches of the sole of a man's foot to be twenty-five (25) and the average of weight to be one hundred and twenty-five (125) pounds; this would give a pressure per square inch of five (5) pounds. Now, if the bands of the machine be one (1) foot wide and the length of each band in contact with the ground be fifteen (15) feet, that would give a bearing surface of thirty (30) square feet or four thousand three hundred and twenty square inches, which, with a pressure of five (5) pounds to the square inch would sustain twenty-one thousand six hundred pounds. Thus a machine constructed in these proportions could carry over twenty thousand pounds (including its own weight) and not bear as heavily on the ground as a man of ordinary weight, and could consequently carry half that weight over ground too soft to support the weight of a man.

Second. There is no possibility of slip. If the bands move at all the machine must move also, because so long as the friction between the bands and the ground is greater than between the bands and the machine the movement of the machine is insured; and while it is true that by adding weight to the machine the friction between it and the bands is increased, that is, the friction on the axles of the rollers, the friction of the bands

on the ground is increased also, and the relative proportion of the friction remains unchanged. The engine may stall by the resistance of the friction between the bands and the machine becoming greater than its power to overcome, which of course depends on the power of the engine and the weight to be carried, but the machine cannot slip.

Third. The machine cannot be slid over the ground, for, to a force exerted for that purpose, it opposes the inertia and the friction of a solid body of the same bearing surface and having the same weight.

Fourth. It will ascend an inclined plane of any angle where the earth will not slide.

Fifth. It will move over obstacles whose abrupt height does not exceed the radius of the curve formed at the end of the frames or runners.

Sixth. It will not bury itself, because the force is exerted in a plane parallel to the line of direction; hence, if by standing still on soft ground it should sink, the operation of the machine would be to draw itself out of the hole and not to bury itself deeper, as is the case with ordinary machines in similar circumstances.

Seventh. The adoption of my machine obviates deep cuts, high embankments, and bridges and tunnels, at least, to a great extent, because it possesses the power of ascending heavier grades than is possible at present.

Eighth. The construction of the machine enables it to run equally well either backward or forward, wholly obviating the necessity of turning, and the consequent loss of time.

Ninth. It forms a perfect power for agricultural purposes, as it will do all the work of a horse and compress the earth less, and can be easily constructed to act as a stationary engine at the same time.

Tenth. It can be turned completely round, when so desired, in the smallest possible space, by simply causing the bands to move in opposite directions.

Having thus described my invention, what I claim as new, and desire to secure by Letters Patent, is—

The grooved rollers B and ribbed band C, in combination with the curved end frame A, bearing the working parts, which communicate motion to the band, constructed and applied as described for the purpose specified.

The above specification of my invention signed by me this 28th day of March, 1866.

R. J. NUNN.
